GASIFICATION OF SOLID FUEL.

Application filed December 5, 1922. Serial No. 605,094.

Our invention relates to improvements in the gasification of fuel and in one of its aspects it is concerned with the gasification of bituminous fuel, and in another of its aspects it is concerned with the avoidance of objectionable clinker in the gasification of hard fuel (coke) or of bituminous fuel for the production of water gas. The invention may be said to comprise the intermittent agitation of the top of the fuel bed in order to increase production, and the agitation of the top of the fuel bed to avoid the production of undesirable clinker in the case of water gas production.

In the operation of gas producers or water gas generators for the production of gas from bituminous fuel one of the factors limiting the rate of production of gas, or otherwise stated, the capacity of the producer or generator is the emission at the top of the fuel bed and the carrying over with the gas of fuel particles, a certain amount of which is put up with by removing it from the gas receiving flues and apparatus but nevertheless such carrying over operates to limit the rate at which the producer or generator can be commercially operated. Aside from the above the use of bituminous fuel or even of coke presents certain well known difficulties peculiar to the manufacture of water gas and involving the formation of objectionable clinkers which limit the rate of gas production.

Objects of the present invention are to minimize, and even make negligible the quantity of fuel particles that are carried over from the fuel and, if desired, to permit of an increase in the rate of blast and of the gasification of fuel resulting of course in an increase in the rate of production of gas in the case of any given generator or producer.

Another object of the present invention is to counteract the tendency towards abnormal changes in temperature of a fuel bed, blasted alternately with steam and air for the production of water gas, due to the formation of channels or "chimneys", and which cause the fusion or agglomeration of ash into masses of clinker adherent to the side wall of the generator, and elsewhere, high up in the fire and which masses of clinker are difficult to remove and if not removed limit the rate of production of gas in addition to causing waste of steam.

The invention will be claimed at the end hereof but will be first described.

The accompanying drawing is diagrammatically illustrative of the process and in it Fig. 1 is a vertical sectional view illustrative of the step of utilizing the voids in quiescent fresh fuel for diffusing the blast.

Fig. 2 is a vertical sectional view illustrative in an exaggerated manner of a condition to be avoided in the process in which the efficiency of the voids for the purpose of Fig. 1 has been unduly diminished prior to the supply of additional fuel, and

Fig. 3 is a vertical cross section illustrating the restored porosity in advance of the next oncoming supply of fuel.

For the sake of a description reference may be made to the gasification in a producer or generator of a bed of fuel to the top of which bituminous fuel is fed in fairly even distribution and which is upwardly blasted in a manner well understood for the production of producer or water gas. Such a process is cyclic, in that succeeding supplies of fuel fed at the top of the fuel bed descend through the fuel bed being covered by oncoming supplies of fuel. By permitting the supplies of fuel at the top of the fuel bed to remain substantially or sufficiently quiescent, the voids naturally occurring between the particles of bituminous fuel afford passages for the blast which are distributed substantially uniformly throughout the horizontal extent or area of the fuel bed.

From this it follows that the supply of bituminous fuel at the top of the fuel bed is blasted very uniformly throughout its extent as distinguished from violent concentration of the blast at localized portions, so that the entire horizontal extent of the top supply of fuel is uniformly heated and not disturbed in a way that would give rise to the emission of fuel particles, and in this connection it may be said that if the effect of the blast is localized the blast is sufficiently strong to blow over fuel particles, but by putting the blast uniformly through the top supply of fuel the blast is not strong enough to blow over any substantial quantity of fuel particles.

Under the heat of the blast and in most cases the fuel at the top part of the fuel bed sears and melts and becomes sticky or otherwise changes its condition so that the voids between the particles of the fuel

lose or tend to lose their efficiency as a medium for permitting the blast to be uniformly distributed. Upon or prior to this occurrence the supply of fuel at the top of the fuel bed is stirred and a fresh supply of fuel is fed on top of it. The effect of the stirring is to slice or sub-divide the agglomerations of seared, melted or rearranged fuel, thus making passages through which the blast in substantially uniform horizontal distribution reaches the oncoming supply of fuel. Inasmuch as particles of bituminous fuel carbonize from the surface inward, it follows that the described application of heat first to the surface of the particles as they exist in the fuel and then to the surface of the sliced or divided agglomerations is a rapid and economical one. The uniform distribution of the passage of the blast through the supply or supplies underlying the top and quiescent fuel operating in the manner above described is not productive of localized blasts and therefore does not tend to blow fuel particles out at the top of the fuel bed.

25 When my invention is applied to a water gas generator steam may be introduced to the fuel bed through the inlet labeled "steam" in Figure 1.

Without intending to limit the invention but in order to further describe the same its practice in the following form may be referred to:

Referring to Fig. 1, bituminous coal is fed in substantially evenly distributed supplies on the top of the fire which is upwardly air blasted at 1, the fuel supply 2 at the top of the fuel bed being undisturbed is permitted to sear or melt or become sticky under the influence of the heat of the blast, for example, for from five to ten minutes, or as long as desired without unduly increasing the resistance of the fire to blast or gas passage so that no substantial amount of fuel is carried over or objectionable holes made through the top layer, and at the end of that time stirring the supply and feeding additional supplies. The condition approached but avoided, as above described, is shown in

Fig. 2 in which 3 indicates the holes in the fire and 4 indicates dust carried over. 6 is a stirrer. In the illustration just given the fuel is fed intermittently and the fuel bed underlying the supply at the top is stirred intermittently but it is not in all cases necessary that these steps be strictly intermittent although that practice produces excellent results. Fig. 3 illustrates the fuel bed stirred and restored to the condition of Fig. 1 prior to the arrival of the next supply of fuel 5, which in its turn operates when quiescent as described in connection with Fig. 1.

The occurrence of localized air blasts through vents or chimneys in the fuel bed in the case of the gasification of soft or hard fuel in the production of water gas is productive of masses of clinker adherent to the side wall of the generator or located throughout the fuel bed, high above the grate, because the temperature of the fire is alternately unduly raised and lowered as hereinabove described, and this is one of the cases in which the agitation of the hard fuel need not be intermittent.

It will be obvious to those skilled in the art to which the invention relates that modifications may be made in details of practice and procedure without departing from the spirit of the invention which is not limited as to those matters or otherwise than as the prior art and the appended claim may require.

We claim:

A process of making combustible gas from bituminous fuel; which consists in charging bituminous fuel into a gas producer so as to form a fuel bed having voids between the fuel lumps therein; then air blasting the fuel bed, while it remains quiescent, to form combustible gas until the top portion of the fuel bed is coalesced and the voids partly eliminated; then stopping the air blast; then stirring the coalesced fuel portion; then adding additional bituminous fuel; and then air blasting the fuel bed.

JOHN M. RUSBY.
